UNITED STATES PATENT OFFICE.

JULIUS STEINBERG, OF NEW YORK, N. Y.

HEAD GEAR AND METHOD OF MAKING THE SAME.

Application filed June 27, 1927. Serial No. 201,775.

This invention relates to improvements in head gear and methods of making the same and has particular reference to a lady's hair net.

- 5 The primary object of the invention resides in a lady's hair net or boudoir cap for sport wear or for use at night for keeping the hair in a set position during the sleep of the wearer.
- 10 Another object of the invention is to provide a head gear made of a net material in which the outer edge of the head gear is bound by a length of separate fabric or ribbon and which ribbon is stitched to the
- 15 net body during the knitting operation of the same whereby much time and labor is saved, as the practice of stitching the two parts separate would require a separate operation.
- 20 A further object of the invention is the provision of a head gear consisting of a body of knitted material having an outer edge of a separate material such as a fabric ribbon but which permits the net body to be knitted in a manner to produce a relatively loose open weave which is capable of considerable stretch without distorting the shape of the head gear.

A still further object is to provide a method of manufacturing knitted head gear which increases the production and reduces the cost in comparison to the method now commonly used for this purpose.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a view showing my improved head gear in position upon the head of a wearer.

Figure 2 is an enlarged plan view of a portion of the head gear in a flat condition before being formed into cap shape.

Figure 3 is a transverse sectional view on the line 3—3 of Figure 2.

Figure 4 is a greatly enlarged fragmentary sectional view of the means for attaching the outer edge of the knitted body to the ribbon or binding tape.

Referring to the drawing by reference characters, the numeral 10 designates my improved head gear in its entirety which

includes a knitted net body 11, an outer fabric band 12 and an inner elastic edge 13.

The body 11 may be made of any suitable thread such as rayon silk and which is 60 knitted on the flat type of knitting machine to form relatively large pore chain stitches 14 which form rows of wavy strands which are joined together by loops 15 of the sliding cross bar threads 16 which are interlaced 65 through the chain stitching as clearly shown in Figure 4 of the drawings. These cross bar threads may be coarser than the silk thread from which the strands of the net are formed and which are slidable through 70 the links of the chain strands to afford the net ample means for stretching.

The band 12 is a separate piece entirely from the net body and is fed into the knitting machine in a manner similar to the 75 threads from which the net is knitted. The band however, is attached to the outer edge of the net body during the knitting of the body by providing a separate stitching needle in the knitting machine which produces stitching 17 along the length of the band and which stitching overlaps the outer loops 15 of the cross bar threads whereby the band is fixedly attached to the net body.

The inner edge of the net body 11 has 80 an elastic thread 18 woven in zig-zag form into the end strand of chain stitching to allow the material to cover the elastic thread for producing a tubular covering 19 therefor.

The material from which the head gear is constructed passes out of the knitting machine in a continuous flat piece as shown 85 in Figure 2 of the drawing, after which it is cut into pieces of predetermined lengths and the adjacent ends fastened together to draw the piece into cap shape, the ends of the elastic band being bunched to reduce the length of the same to cause the elastic band to normally gather the back of the head gear whereby it may be stretched or expanded over the head of a wearer and fit tight thereon.

Although I have specifically mentioned certain materials, it will be appreciated that other materials may be used if desired, such as a knitted mesh design of cotton, wool, braid, pure silk or a mixture of any of the above. The binding or reinforcing band 100 may also be of various materials but must be a separate piece from the knitted mesh material.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

10. What is claimed as new is:—

1. As a new article of manufacture, a head gear comprising a knitted mesh body, a fabric band separate from said body, and means for attaching said band to one edge of said body, the opposite edge of said mesh body having a tubular passage formed therein, and an elastic thread passing through said tubular passage.

2. In a new article of manufacture, a knitted mesh body having loops along an edge thereof, a fabric band, stitching passing through said band and overlying said loops for fixedly connecting said fabric band to said mesh body, another edge of said body having a tubular passage formed therein, and an elastic thread passing through said tubular passage.

3. The method of making head gear

which consists in knitting a mesh body by strands of chain stitches and interlacing 30 sliding cross bar threads through the strands of chain stitches, attaching a fabric band to one of the side edges of said mesh body during the knitting of the same by passing stitching through the band with the stitching overlapping the cross bar threads on said side edge.

4. The method of making head gear which consists in knitting a mesh body by strands of chain stitches and interlacing 40 sliding cross bar threads through the strands of chain stitches, attaching a fabric band to one of the side edges of said mesh body during the knitting of the same by passing stitching through the band with the stitching overlapping the cross bar threads on 45 said side edge and knitting a tubular covering along the opposite edge of the mesh body about an elastic thread.

5. The method of making head gear 50 which consists in stitching a fabric band to the edge of a knitted mesh body during the knitting thereof.

In testimony whereof I have affixed my signature.

JULIUS STEINBERG.
